US00D768729S

(12) **United States Design Patent** (10) Patent No.: **US D768,729 S**
(45) Date of Patent: **** Oct. 11, 2016**

(54) **ON ROW HOPPER AND LID**

(71) Applicant: **CNH Industrial America LLC**, New Holland, PA (US)

(72) Inventors: **Scott A. Long**, Plainfield, IL (US); **Douglas V. Montgomery**, Downers Grove, IL (US); **Henry Tran**, Elk Grove Village, IL (US); **Christopher Schoeny**, Yorkville, IL (US); **Chad M. Johnson**, Arlington Heights, IL (US)

(73) Assignee: **CNH Industrial America LLC**, New Holland, PA (US)

(**) Term: **15 Years**

(21) Appl. No.: **29/531,812**

(22) Filed: **Jun. 30, 2015**

(51) LOC (10) Cl. **15-03**

(52) U.S. Cl.

USPC **D15/28**; D15/27; D15/10

(57) **CLAIM**

The ornamental design for the on row hopper and lid, as shown and described.

DESCRIPTION

FIG. 1 is a perspective view of the on row hopper and lid showing our new design, the portion in phantom lines in the figures forming no part of the claimed invention;

FIG. 2 is a side view thereof;

FIG. 3 is an opposite side view thereof;

FIG. 4 is front view thereof;

FIG. 5 is a rear view thereof;

FIG. 6 is a top view thereof; and,

FIG. 7 is a bottom view thereof.

1 Claim, 7 Drawing Sheets
